(57) **CLAIM**

The ornamental design for an infrared heating apparatus, as shown and described.

DESCRIPTION

FIG. 1 is a front-left perspective view of an infrared heating apparatus, showing my new design;

FIG. 2 is a front elevational view thereof;

FIG. 3 is a back elevational view thereof;

FIG. 4 is a top plan view thereof;

FIG. 5 is a left side elevational view thereof; and,

FIG. 6 is a right side elevational view thereof.

1 Claim, 6 Drawing Sheets

FIG. 1

FIG. 2

FIG. 3

FIG. 4

FIG. 5

FIG. 6
